ELECTRIC IRON

Kenneth Grange, London, England, assignor to Morphy-Richards Limited, Kent England, a company of Great Britain

Filed Mar. 15, 1967, Ser. No. 6,224

Claims priority, application Great Britain Sept. 28, 1966

Term of patent 14 years

(Cl. D49—6)

FIG.1

FIG.2

FIG.3

FIG.4

FIGURE 1 is a side perspective view of an electric iron, embodying my new design.

FIGURE 2 is a front perspective view thereof.

FIGURE 3 is a rear perspective view thereof, and

FIGURE 4 is side view showing the other side from that shown in FIGURE 1.

The dominant features of my design reside in the portions shown in full lines.

I claim:

The ornamental design for an electric iron, as shown and described.
